UNITED STATES PATENT OFFICE.

EDWARD M. KING, OF MILFORD, MASSACHUSETTS, ASSIGNOR TO KING GRANITE MACHINE COMPANY, OF MILFORD, MASSACHUSETTS, A CORPORATION OF MASSACHUSETTS.

STONE-CUTTING MACHINE.

1,209,727.

Specification of Letters Patent. Patented Dec. 26, 1916.

Application filed November 27, 1915. Serial No. 64,186.

To all whom it may concern:

Be it known that I, EDWARD M. KING, a citizen of the United States of America, and a resident of Milford, in the county of 5 Worcester and State of Massachusetts, have invented certain new and useful Improvements in Stone-Cutting Machines, of which the following is a specification.

This invention relates to stone working 10 machines and has for its object the production of a machine of this character which is adapted to be propelled over stationary tracks along one side of a stone the face of which it is desired to finish.

15 Another object of the invention is to provide a traveling machine of this character with a revoluble wheel carrying a plurality of rotary cutters which may be moved toward and from the outer face of said wheel 20 and to any desired angle relatively thereto.

The invention consists of certain novel 25 features of construction and arrangement of parts which will be fully understood by reference to the description of the drawings and to the claims hereinafter given.

Of the drawings: Figure 1 represents a 30 plan of a machine embodying the principles of the present invention. Fig. 2 represents a vertical longitudinal section of the same, on line 2—2 on Fig. 1. Fig. 3 represents a transverse vertical section on line 3—3 on Fig. 2. Fig. 4 represents an elevation of one of the cutter-carrying revoluble wheels. Fig. 5 represents an elevation of a portion of 35 one of said wheels, partly in section, and showing the adjustable supports for the rotary cutters. Fig. 6 represents a sectional detail of the same, on line 6—6 on Fig. 5, and Fig. 7 represents a detail to be herein- 40 after described.

Similar characters designate like parts throughout the several figures of the drawings.

In the drawings, 10 is a supporting frame 45 having secured to the under face thereof a plurality of flanged wheels 11 adapted to travel along the stationary tracks 12 in a straight path. Secured to the upper face of the supporting frame 10 is a weighted frame 50 13 provided with alined bearings in which is mounted a revoluble shaft 14 to the opposite ends of which are secured the wheels 15. Centrally disposed between the wheels 15 and keyed to the shaft 14 is a gear 16 with

the teeth of which mesh the teeth of a pinion 55 17 secured to a shaft 18 mounted in suitable bearings on the frame 13. One end of the shaft 18 is provided with the pulley 19 to which rotary movement is imparted by a belt 20 passing around a small pulley 21 60 upon the shaft 22 of a suitable electric motor 23 or some similar device. The pulley 21 is on one end of the shaft 22 while on its opposite end is a similar pulley 24 by which rotary movement is imparted through the 65 belt 25 to the pulley 26 mounted upon a transverse shaft 27. This shaft 27 has mounted thereon a pinion 28 the teeth of which mesh with the gear 29 keyed to a rotary shaft 30 mounted in bearings on the 70 supporting frame 10. The teeth of the gear 29 engage with the teeth of a stationary rack 31 and as the shaft 30 is rotated by means of the motor 23 it is obvious that the carriage or supporting frame 10 will be moved in a 75 straight path over the tracks 12 in either direction in accordance with the direction of rotation of the shaft 30. The shaft 27 has also secured thereto a pulley 32 operating through the medium of a belt 33, a blower 80 34 of any well-known construction, this blower being provided to remove the dust during the stone finishing operation. Each wheel 15 is provided with a plurality of pins 85 35 extending through the rim thereof and threaded thereto so that by turning either of said pins 35 it will be moved lengthwise relatively to the face of the wheel 15.

The ends of each pin 35 extend considerably beyond the parallel faces of the rim of 90 the wheel 15. Each pin extends through the bifurcated or forked support 36 as shown in Fig. 6 of the drawings, the outer end of the pin being provided with the head 37 which bears against the outer face of the 95 support 36 while the opposite end of said pin is threaded and has mounted thereon the washer 38 and check nut 39, while a pin 39^x extends through the end thereof. Each pin 35 is located in the rim of the wheel 15 adjacent to one of the spokes 40 of the wheel 15, and the supporting member 36 is provided on opposite faces with ribs 41 and 42 which engage with the inner cylindrical face of the rim of the wheel 15, thus preventing 105 any movement of the support 36 about the axis of the pin 35.

Inside of the rim of the wheel 15 the sup-

port 36 is provided with a conical opening 43 into which is fitted the flaring conical head 44 of a block 45. The block 45 extends beyond the face 46 of the support 36 and has a diam-
5 etral opening or slot 47 extending therethrough in which is mounted an arm 48 the outer end of which is provided with a cylindrical hub 49 in which is mounted a sleeve 50. The block 45 has threaded thereto a
10 clamping bolt 51 which may be loosened to permit the arm 48 to be moved endwise in the slot 47 and to permit the block 45 to be rotated about its axis relatively to the support 36, thereby moving the arm 48 to any
15 desired angle relatively to the outer face of the wheel 15. When the arm 48 has been moved lengthwise and about the axis of the block 45 sufficiently to adjust it to a desired angle relatively to the wheel 15, the clamp-
20 ing bolt 51 is operated to force the rear face of the arm 48 against the face 46 of the support 36. The same operation of the clamp-
25 ing bolt 51 will force the block 45 outwardly so that the cone-shaped peripheral portion 44 thereof will impinge upon the conical wall of the opening 43 and lock the block 45 and the arm 48 in their adjusted position.
The block 45 is provided with an index 52 which coacts with the graduations 53 on the
30 face 46 of the support 36, thereby making it possible to immediately position the arm 48 at any predetermined angle. The sleeve 50 is provided with a head 54 bearing against one end of the cylindrical hub 49 while the
35 other end of said sleeve is surrounded by a washer 55 and is threaded to receive a nut 56 and check nut 57 by which said sleeve may be clamped securely in position in the said hub 49.
40 A shaft 58 extends through the sleeve 50 and at one end is provided with an enlarged conical head 59 on which is mounted a rotary steel cutting disk 60. Between this disk 60 and the head 54 of the sleeve 50 is interposed a washer 61 surrounding the shaft 58 the
45 opposite end of which is provided with a cotter pin 62 extending therethrough to prevent the displacement of said shaft 58. This construction is clearly shown in Figs. 5 and
50 6 of the drawings. Preferably when the machine is in operation all of the cutting disks 60 mounted upon one of the wheels 15 are positioned at the same angle relatively to the outer face of said wheel 15, but it is ob-
55 vious that for various classes of work the angularity of these disks may be changed at will. The cutting disks 60 may be located in the same cutting plane if desired, or each cutting disk may be adjusted relatively to
60 the others so that during the rotation of the wheel 15 one cutting disk 16 will remove a certain amount from the stone and the next succeeding cutting disk will remove a fur-
65 ther amount from the stone in a different plane.

Any number of cutting disks 16 may be mounted upon the wheels 15, these cutting disks being equally spaced around the rim thereof and preferably the disks on one wheel are positioned intermediate to the 70 disks on the other wheel in order that there may be a continuous cutting as the two wheels 15 rotate, thereby distributing the strain evenly over the entire machine.

When it is desired to locate the cutting 75 disks 60 in different planes relatively to the outer face of the revoluble wheel 15 the pin 35 is rotated sufficiently to cause the required movement of the support 36 in a path perpendicular to the front face of the rim of 80 the wheel 15.

The tracks 12 and the rack 31 are mounted upon a suitable framework 63 which also has mounted thereon suitable supports 64 on which the stone 65 to be operated upon is 85 mounted. The weight of the stone may be in some cases sufficient to prevent any displacement thereof during the cutting or finishing operation, but preferably the stone 65 is clamped to the supporting members 64 in 90 any well known manner.

If desired, provision may be made for supporting the stone upon a movable table 66 as shown at the right of Fig. 3 of the drawings. The table 66 is pivoted at 67 and may be 95 inclined as desired by the operating wheel 68, this operating wheel being mounted upon a shaft 69 having a bevel gear 70 meshing with a similar gear 71 on a shaft 72, the opposite ends of which have keyed thereto 100 pinions 73 each meshing with a rack 74 on a vertical support 75. When the wheel 68 is turned the vertical support 75 beneath the table 66 will be raised and lowered, causing said table 66 to move about its pivot 67 into 105 the desired inclined position.

The supports 75 and the supports 76 carrying the pivot 67 are mounted in vertical bearings 77 in the frame 78 adapted to be moved horizontally on the tracks 79 by 110 means of the revoluble screw 80 threaded to the nut 81 formed upon or secured to the table 66. The screw 80 is provided with a head 81 engaged in a socket 82 adapted to prevent end movement of the screw 80 while 115 permitting the free rotation thereof. The lower end of each of the supports 75 and 76 is provided with a female screw thread which is engaged by a vertical screw 83 to the lower end of which is secured a pinion 120 84, the four pinions 84 all meshing with a central gear 85. One of the pinions 84 has secured to its hub a bevel pinion 86 meshing with a gear 87 adapted to be rotated by the handle 88. As the gear 87 is rotated by 125 means of the handle 88, rotary movement will be imparted to the gear 85, and all of the pinions 84 will rotate in unison and turning the screws 83 to which they are secured, the raising and lowering of the stone 130

supporting table will be attained. It is obvious by these various adjustments the stone placed upon the table 66 may be treated in many different ways and have surfaces thereon finished at any desired angle or curvature.

5 An adjustable gage 90 is mounted upon the frame 63 to indicate the lowest point in the path of movement of the cutting disks 60 as it revolves with the wheel 15.

10 When the traveling carriage has moved sufficiently to disengage the cutting disks from the stone, provision can be made for reversing the movement of the motor and cause the carriage to move in the opposite

15 direction. As any form of mechanism adapted for this purpose may be used, and such mechanism forms no part of the present invention, it is not shown or described.

20 This makes a very inexpensive device for cutting and dressing stones which is very effective in its operation. The many advantages of this invention it is believed will be fully understood from the foregoing description.

25 Having thus described my invention, I claim:

1. In a machine of the class described, the combination of a revoluble wheel; a support mounted on said wheel; a radial arm mounted on said support and adjustable outwardly from the plane of rotation of said wheel; and a rotary cutting disk on the outer end of said arm with the cutting edge outside the periphery of said wheel.

30 2. In a machine of the class described, the combination of a revoluble wheel; a forked support mounted on said wheel and secured thereto by a pin parallel to the axis of said wheel; an arm mounted on said support and adjustable outwardly from the plane of rotation of said wheel; and a rotary cutting disk on the outer end of said arm.

35 3. In a machine of the class described, the combination of a revoluble wheel; a support adjustably mounted thereon and movable in a direction parallel to the axis of said wheel; an arm pivotally mounted on said support; a rotary cutting disk mounted on the outer end of said arm; and means for clamping said arm in adjusted position.

40 4. In a machine of the class described, the combination of a revoluble wheel; a support adjustably mounted thereon and movable in a direction parallel to the axis of said wheel; an oscillating block on said support; an arm radially positioned on said block; a rotary cutting disk mounted on the outer end of said arm; and means for clamping said block in adjusted position.

45 5. In a machine of the class described, the combination of a revoluble wheel; a support mounted thereon having a conical opening therein and adjustable transversely of said wheel; a block fitting said opening in said support; an arm radially positioned on said

block; a rotary cutting disk mounted on the outer end of said arm; and means for clamping said block in adjusted position.

6. In a machine of the class described, the combination of a revoluble wheel; a support mounted thereon having a conical opening therein and adjustable transversely of said wheel; a block having a flaring end fitting said opening and provided with a slot perpendicular to said axis; an arm mounted in said slot; means for clamping said arm and block to said support in adjusted positions; and a rotary cutting disk on the outer end of said arm.

7. In a machine of the class described, the combination of a revoluble wheel; a support having a conical opening therein and so mounted on the rim of said wheel so as to be adjustable transversely thereon; a block having a flaring end fitting said opening and provided with a slot perpendicular to its axis; an arm mounted in said slot; a single means for clamping said arm and block to said support in adjusted positions; and a rotary cutting disk on the outer end of said arm.

8. In a machine of the class described, the combination of a revoluble wheel; a pin threaded thereto with its axis parallel to the axis of said wheel; a bifurcated support mounted on said pin and adjustable parallel to the axis of said wheel by the rotation of said pin; an oscillating arm mounted on said support; means for locking said arm in adjusted position; and a rotary cutting disk on the outer end of said arm.

9. In a machine of the class described, the combination of a revoluble wheel; a pin threaded thereto with its axis parallel to the axis of said wheel; a bifurcated support mounted on said pin and adjustable parallel to the axis of said wheel by the rotation of said pin; an oscillating arm mounted on said support and adjustable lengthwise relatively thereto; means for locking said arm in adjusted position; and a rotary cutting disk on the outer end of said arm.

10. In a machine of the class described, the combination of a supporting frame; means for moving said frame in a straight path; a revoluble shaft transversely mounted in said frame; a wheel on the end of said revoluble shaft; and a plurality of rotary cutting disks mounted on said wheel with their faces inclined to the face of said revoluble wheel.

11. In a machine of the class described, the combination of a supporting frame; means for moving said frame in a straight path; a revoluble shaft transversely mounted in said frame; a wheel on the end of said revoluble shaft; a plurality of rotary cutting disks mounted on said wheel; means for adjusting the angular positions of said disks relatively to said wheel; and means

for moving said disks perpendicularly to the face of said wheel and at the same time retain the same in inclined relation to the face of said wheel.

5 12. In a machine of the class described, the combination of a supporting frame; means for moving said frame in a straight path; a revoluble shaft transversely mounted in said frame; a wheel on the end of said

10 revoluble shaft; a plurality of rotary cutting disks mounted on said wheel; means for adjusting the cutting edges of said disks at various distances from the face of said wheel; and means for retaining all of said 15 disks at the same inclination relatively to said wheel.

13. In a machine of the class described, the combination of a revoluble wheel having a rim and radial spokes; a forked support 20 adapted to straddle said rim and extending inwardly therefrom, said support being provided with rim engaging members to prevent movement about its connection with said rim; means for moving said support 25 transversely of said rim; an arm pivotally mounted on said support and having provision for end movement; and a rotary cutting disk on the end of said arm.

14. In a machine of the class described, 30 the combination of a revoluble wheel having a rim and radial spokes; a forked support adapted to straddle said rim and extending inwardly therefrom, said support at its inner end bearing against one of said spokes; 35 means for moving said support transversely of said rim; an arm pivotally mounted on said support and having provision for end movement; and a rotary cutting disk on the end of said arm.

40 15. In a machine of the class described, the combination of a revoluble wheel having a rim; a pin extending transversely through said rim and threaded thereto; a forked sup-

port mounted upon said pin; means preventing movement of said support about the 45 axis of said pin; means for moving said support transversely of said rim by the rotation of said pin; an arm adjustable endwise and pivotally mounted on said support; and a rotary cutting disk mounted on the 50 outer end of said arm.

16. In a machine of the class described, the combination of a revoluble wheel having a rim; a pin extending transversely through 55 said rim and threaded thereto; a forked support mounted upon said pin; means preventing movement of said support about the axis of said pin; means for moving said support transversely of said rim by the rotation of said pin; an arm adjustable endwise and 60 pivotally mounted on said support; a shaft extending transversely of the outer end of said arm; and a rotary cutting disk mounted on the outer end of said shaft.

17. In a machine of the class described, 65 the combination of a revoluble wheel having a rim; a pin extending transversely through said rim and threaded thereto; a forked support mounted upon said pin; means preventing movement of said support about 70 the axis of said pin; means for moving said support transversely of said rim by the rotation of said pin; an arm adjustable endwise and pivotally mounted on said support; a shaft extending transversely of the 75 outer end of said arm having an enlarged conical head; and a rotary cutting disk mounted on the outer end of said enlarged conical head.

Signed by me at Milford, Massachusetts, 80 this 23d day of November, 1915.

EDWARD M. KING.
